UNITED STATES PATENT OFFICE

133,717

DESIGN FOR A COMBINED SACHET AND CONTAINER

Albert H. Newman, Chicago, Ill.

Application July 30, 1942, Serial No. 107,764

Term of patent 3½ years

To all whom it may concern:

Be it known that I, Albert H. Newman, a citizen of the United States, residing at Chicago, in the county of Cook and State of Illinois, have invented a new, original, and ornamental Design for a Combined Sachet and Container, of which the following is a specification, reference being had to the accompanying drawing, forming part thereof.

In the drawing,

Fig. 1 is a side elevational view of a combined sachet and container showing my new design; and

Fig. 2 is a top plan view thereof.

I claim:

The ornamental design for a combined sachet and container, as shown.

ALBERT H. NEWMAN.
